TOOTH CLEANER

Sam Women Sam, Chicago, Ill.

Application October 30, 1951, Serial No. 253,928

7 Claims. (Cl. 132—91)

1

The invention relates to a tooth cleaner which is a substitute for dental floss and tooth picks. This application is a continuation-in-part of my copending application for Tooth Cleaner, Serial Number 76,050, filed February 12, 1949, and now abandoned.

The main object of the invention is to devise a tooth cleaner which serves as a substitute for dental floss and tooth picks and which does not bruise nor irritate nor otherwise harm the gums and which, on the contrary, has a beneficial massaging effect on the gums.

Other objects and advantages become apparent as the description proceeds.

I attain these objects by devices illustrated in the accompanying drawing, in which—

Figure 1 is an axial sectional view of the preferred form of the tooth cleaner;

Figure 2 is an axial sectional view of an alternative form of the tooth cleaner; and

Figure 3 is a right cross-sectional view of the tube 7 along plane A—A.

In Figure 1 is shown a tube 5 assembled ready for use on a U-frame and secured to U-frame 1 by a pair of suitable rubber bands 3. U-frame 1 has a handle 6 and a pair of coaxial, cylindrical cores 4. Each core 4 is rigidly fastened to each end of U-frame 1 and projects perpendicularly, transversely in opposite directions inwardly and outwardly from each end of U-frame 1. Tube 5 which is made of natural rubber latex and is extremely thin has a principal horizontal portion both ends of which are closed. The principal horizontal portion of tube 5 has a pair of lateral apertures. Each aperture is located near each closed end of the principal horizontal portion of tube 5. Tube 5 also has a pair of transversely, vertically, perpendicularly extending short tubes 2. An edge of the inner end of each transversely extending tube 2 is integral with the edge of each lateral aperture of the principal horizontal portion of tube 5. The outer end of each transversely extending tube 2 is flared to facilitate the assembly of tube 5 on cores 4 together with the ends of U-frame 1. Each core 4 is enveloped by each closed end of the principal horizontal portion of tube 5 and lies longitudinally in the principal horizontal portion of tube 5 and each end of U-frame 1 is enveloped by each transversely extending tube 2 when tube 5 together with its pair of transversely extending tubes 2 are assembled with cores 4 and U-frame 1. Each rubber band 3 envelopes tightly and securely the portion of each transversely extending tube 2

adjacent to the principal horizontal portion of tube 5 and around each end of U-frame 1 adjacent to each core 4. The assembly of each end of U-frame 1 and each core 4 thus have a form which enables the internal surface of each end of the principal horizontal portion of tube 5 all around its axis to be conveniently unitable securely by means of each rubber band 3 to the peripheral surface of each core 4 all around the axis of each core 4 while tube 5 is assembled with the pair of cores 4 and U-frame 1. Cores 4 are spaced apart a distance exceeding the length of the portion of tube 5 intermediate the cores 4 during normal use, said length to be measured while the intermediate portion of tube 5 is not stretched. While tube 5 is assembled to cores 4 and U-frame 1 then cores 4 cooperate with the ends of tube 5 to enable the tubular form of the intermediate portion of tube 5 to be maintained while the intermediate portion is stretched taut under elastic tension between and spanning across cores 4. The opposite lateral walls of the intermediate portion of tube 5 are drawn together in contact while the intermediate portion of tube 5 is being inserted between two adjacent teeth and spread apart as much as space permits in the space between the two adjacent teeth next to the gums which space is normally wider than the rest of the space between the two adjacent teeth. The intermediate portion of tube 5 is thus automatically thick or thin when necessary. The intermediate portion of tube 5 is inserted between the teeth in a manner similar to the insertion of dental floss which is held in a U-frame. Tube 5 together with its transversely extending tubes 2 is essentially a single tube each of whose open flared ends envelops the inwardly projecting portion of each core 4 together with each end of U-frame 1. The portions of tube 5 which envelop the outwardly projecting portions of cores 4 may be properly viewed as projecting distortions of an ordinary cylindrical tube with flared ends which projecting distortions are located intermediate the open flared ends of the latter tube. The outwardly projecting portions of cores 4 may be eliminated with not much disadvantage and then the ends of a short length of ordinary cylindrical tubing could envelop the inwardly projecting portions of cores 4 together with the ends of U-frame 1. Rubber bands 3 would then hold securely the ordinary cylindrical tube as they hold tube 5.

In Figure 2 is shown a tube 7 assembled ready for use on a U-frame 1. Tube 7 is made of

natural rubber latex and is extremely thin. Tube 7 has both ends closed and a longitudinally extending narrow lateral opening 8. The closed ends of tube 7 are securely held by cores 4. The portion of tube 7 intermediate cores 4 is stretched taut under elastic tension while tube 7 is assembled on cores 4 of U-frame 1. In use the portion of tube 7 intermediate cores 4 is inserted between the teeth in a manner similar to the insertion of the intermediate portion of tube 5.

Tubes 5 and 7 are short, slender, extremely thin, supple, soft, stretchable and elastic.

U-frame 1 is made of a suitable metal. It may also be made of a suitable plastic.

I claim:

1. A tooth cleaner comprising a short, slender, thin, supple, stretchable, elastic, soft tube with closed ends and a longitudinally extending narrow opening, said tube being adapted to serve as a substitute for dental floss.

2. A tooth cleaner comprising a short, slender, thin, supple, stretchable, elastic, soft, principal tube having a pair of small lateral apertures located near each end of said principal tube, said tooth cleaner also comprising a pair of transversely extending, short, slender, thin, supple, stretchable, elastic tubes, an edge of the inner end of each of said transversely extending tubes being integral with the edge of each of said apertures, said principal tube being adapted to serve as a substitute for dental floss.

3. A tooth cleaner as set forth in claim 2 wherein the outer end of each of said transversely extending tubes is flared.

4. A tooth cleaner comprising a short, slender, thin, supple, stretchable, elastic, soft tube with both ends closed, said tube having a pair of small lateral apertures located near each of said closed ends of said tube, said tube being adapted to serve as a substitute for dental floss.

5. A tooth cleaner comprising a short, slender, thin, supple, stretchable, elastic, soft, principal tube with both ends closed, said principal tube having a pair of small lateral apertures located near each of said closed ends of said principal tube, said tooth cleaner also comprising a pair of transversely extending, short, slender, thin, supple, stretchable, elastic tubes, an edge of the inner end of each of said transversely extending tubes being integral with the edge of each of said apertures, said principal tube being adapted to serve as a substitute for dental floss.

6. A tooth cleaner as set forth in claim 5 wherein the outer end of each of said transversely extending tubes is flared.

7. Adapted for use with a tooth cleaner as set forth in claim 5, in combination, a U-frame member, and a pair of short slender core members, each of said core members being fastened securely to each end of said U-frame member and projecting transversely therefrom, each of said core members being enveloped by each of said closed ends of said principal tube and lying longitudinally in said principal tube and each of said ends of said U-frame member being enveloped by each of said transversely extending tubes when said principal and transversely extending tubes are assembled with said pair of core members and said U-frame member.
